MACHINE FOR FACILITATING THE CONNECTING OF TEMPLES WITH LENSES

Charles S. Lanman, Columbus, Ohio

Application April 15, 1940, Serial No. 329,800

3 Claims. (Cl. 10—136)

This invention relates more particularly to means or mechanism for use in rapidly, effectively and economically securing the bridge and/or temples of eye glasses to the lenses. The invention is especially useful where the lenses are of the rimless variety and are perforated to receive the bridge and temple connecting members. The temples and bridges and perforated lenses are commonly supplied by manufacturers to wholesaling opticians and such opticians assemble the parts with the aid of ordinary hand tools and as a consequence there is much inaccuracy in the work and breakage and loss of glass and parts.

The principal object of the present invention is to provide the assembling optician with a machine or means whereby the work referred to is not only greatly improved, facilitated and expedited but the loss referred to greatly reduced. Other objects will appear from the disclosure.

The invention is embodied in the example herein shown and described the features of novelty being pointed out in the claims.

In the accompanying drawing—

Figure 1 is a view of the machine in side elevation with a portion of the left hand housing broken out to show some interior details.

Fig. 2 is a combined top plan and horizontal section, the section being on the line II—II Fig. 1 looking down.

Fig. 3 is a detail sectional view taken on a vertical plane indicated by the line III—III Fig. 2 looking toward the right.

Fig. 4 is a sectional detail view illustrating conventional form of means for connecting an eye glass temple with a lens.

In the views, 5 designates a base on which the parts of the machine are mounted. 6 designates a housing secured on one end of the base, said housing containing a small conventional electric motor provided with a usual plug-in member 7 for supplying the operating electrical circuit to the motor. A switch 8 is provided on the base for controlling the opening and closing of the motor operating circuit.

One end of the rotatable shaft 10 of the motor is provided with a frusto-conical friction clutch 11, preferably of leather, suitably secured to the shaft so as to be rotated with the shaft when the latter is driven.

On the opposite end of the base 5 is secured a second housing 12 in which is mounted a tool holding shaft 13 extending horizontally and at right angles to the axis of the power driven shaft. Said tool holding shaft is journaled at

its opposite end portions in a fixed bushing 14 and in a slidable bushing 15. Near the middle of the said shaft 13 is secured by set screw a spool shaped clutch member 16 the inner sides of the rims of which constitute friction clutch members normally straddling but which in intermediate or neutral position are slightly spaced from the frusto-conical clutch 11. The sliding bushing or sleeve 15 is confined on the tool shaft between said spool-shaped friction member and a collar 17 secured by a set screw on the adjacent projecting end of the tool shaft so that by suitably shifting said slidable sleeve with suitable pressure the spool can be brought into frictional engagement at either side of the frusto-conical friction member to rotate the tool shaft in the direction desired.

A tool for the desired work is shown at 18, it being removably fixed by a set screw on a suitable chuck 19 at the working end of the shaft 13. Said tool commonly has a broach or pyramidal reaming end and a threaded shank portion to fit in and enter the threaded side of the lens engaging strap (see Fig. 4) to clean up the said thread.

The means for shifting the slidable sleeve and the tool holder and its tool includes a handle 20 having a shaft 21 journaled to rock in the housing, said shaft having secured thereto a finger 22, the free end of which engages a notch in the lower side of the slidable bushing 15 as shown in Figs. 1 and 3. A fibre washer is shown at each end of the said slidable bushing 15.

In connecting the strap of a temple or nose piece it is usually found that the prepared holes in the metal parts and the glass are not perfectly aligned. It is therefore necessary to retap the assembled parts before the fastening screw can be properly inserted. It has been the universal custom in the art to use a tool mounted in a small holder and held in the hand to carefully do the retapping. With my machine the operation is as follows: The parts to be treated are held in the hand of the workman and are pressed onto the tool of the machine. This longitudinal pressure engages the tool driving members thereby causes the tapping and reaming of the preformed holes of the metal parts. In this operation it sometimes happens that the tool becomes wedged in the holes by reason of unalignment of such holes and in such cases rotation of the tool is stopped and without my invention the glass of the lens is frequently broken. In my machine the operation, in such event, is this: The parts being treated are withdrawn slightly and the ro-

tation of the tool started by manipulation of the hand lever gently to perform the operation and without forcing it to the degree that would cause breakage of the glass. This may be done with rotation of the tool shaft in either direction as conditions may indicate by means of said hand lever.

The effect of the operation is to remove burrs or irregularities of the openings in both the lens and the metal of the strap of the temple so that the screw securing said strap to the lens can be easily and properly applied.

As the rotary motion of the tool is quite rapid with the electric motor, it is important that the heads of the spool shaped member be made thin and of light weight to reduce momentum due to prolonged rotations of the tool holder and tool pending the change from working position to withdrawing operation of the tool. Usually it is not necessary to employ the handle 20 in operating the tool because the axial pressure of the work against the tool in either direction is sufficient to set it in motion for the operation but said handle is useful if the tool sticks or takes too big a bite. Such manual control of the rotation of the tool is a valuable and time-saving feature.

The forms of the parts can be changed without departing from the gist of the invention as claimed.

What I claim is:

1. A machine for use in reforming the pre-formed holes in the lenses and metal parts of rimless eye glasses for perfecting the connection of the temples and frames and while such a glass and said metal parts are held in a hand of the workman, said machine including a suitable support having journaled thereon a power shaft, a substantially horizontally positioned rotatable shaft having secured on one end thereof a combined reaming and thread-tapping tool, and a stop on its other end, a motion reversing means on said power and tool holding shafts whereby the direction of rotation of said tool holding shaft and the tool thereon can be reversed by longitudinal movement of said tool holding shaft, said means including a bushing longitudinally slidable

on said tool shaft between said stop and the said motion reversing means and a manually controlled means engaging said bushing to shift said motion reversing element.

5 2. A machine for use in reforming the pre-formed holes in the lenses and metal parts of rimless eye glasses for perfecting the connection of the temples and frames and while such a glass and said metal parts are held in a hand of the workman, said machine including a suitable support having journaled thereon a power shaft, a substantially horizontally positioned rotatable shaft having secured on one end thereof a combined reaming and thread-tapping tool, and a stop on its other end, a motion reversing means on said power and tool holding shafts whereby the direction of rotation of said tool holding shaft and the tool thereon can be reversed by longitudinal movement of said tool holding shaft, said means including a bushing longitudinally slidable on said tool holding shaft between said stop and the said motion reversing means, a fibre washer on said shaft adjacent each end of said bushing, and a manually controlled means engaging said bushing to shift said motion reversing element.

3. A machine for use in reforming the pre-formed holes in the lens and metal parts of a rimless eye glass for perfecting the connection of said metal parts with the lens and while such a lens and said metal parts are held in the hand of the workman, said machine including a suitable support having journaled thereon a power shaft, a substantially horizontally positioned rotatable shaft driven by said power shaft and having secured on one end thereof a combined reaming and thread-tapping tool, motion reversing means on said power and tool holding shafts whereby the direction of rotation of said tool holding shaft and the tool therein can be reversed by longitudinal movement of said tool holding shaft by manual pressure on the article treated, and manually controllable means for longitudinally shifting said tool holding shaft independently of the pressure of the hand on the article treated.

CHARLES S. LANMAN.
